(57) **CLAIM**

The ornamental design for a foldable box, as shown and described.

DESCRIPTION

FIG. 1 is a perspective view of the foldable box showing the new design in a flat, unfolded configuration.

FIG. 2 is a front elevational view of the foldable box of FIG. 1.

FIG. 3 is a left elevational view of the foldable box of FIG. 1.

FIG. 4 is a right elevational view of the foldable box of FIG. 1.

FIG. 5 is a top plan view of the foldable box of FIG. 1.

FIG. 6 is a bottom plan view of the foldable box of FIG. 1.

FIG. 7 is a back plan view of the foldable box of FIG. 1.

FIG. 8 is a perspective view of the foldable box of FIG. 1 in an assembled configuration.

FIG. 9 is a top plan view of the foldable box of FIG. 8.

FIG. 10 is a left elevational view of the foldable box of FIG. 8.

FIG. 11 is a right elevational view of the foldable box of FIG. 8.

FIG. 12 is a front elevational view of the foldable box of FIG. 8.

FIG. 13 is a back elevational view of the foldable box of FIG. 8.

FIG. 14 is a bottom plan view of the foldable box of Figure. The foldable box includes symbolic break lines along its length. The break lines and areas between the break lines form no part of the claimed design.

The separations and brackets in FIGS. 1, 2, 5, 6, and 7 are used to indicate that any portions of the foldable box between the separations form no part of the claimed design.
